(57) **CLAIM**

The ornamental design for a sales display stand, as shown and described.

DESCRIPTION

FIG. 1 is a right front perspective view of our new sales display stand;
FIG. 2 is a left front perspective view of our new sales display stand of FIG. 1;
FIG. 3 is a side elevational view of our new sales display stand of FIG. 1;
FIG. 4 is a side elevational view of our new sales display stand from a side opposite that of FIG. 3; and,
FIG. 5 is an end view of our new sales display stand of FIG. 1, the opposite end being a mirror image thereof.
